UNITED STATES PATENT OFFICE

THEODORE CHULANOVSKI, OF DETROIT, MICHIGAN

HAIR CLIPPING MACHINE

Application filed January 7, 1929. Serial No. 330,872.

My invention relates to a new and useful improvement in a hair clipping machine of the power operated type and has for its object the provision of a machine of this class provided with mechanism whereby the clipper may be used to cut the hair close to the scalp or at any desired height from the scalp and whereby the clipper during its travel over the scalp may be adjusted so as to clip the hair at different lengths and uniform all over the scalp to provide the proper depth of cut and eliminate, to a large extent, the operation of trimming with the scissors after the clipper has been used.

Another object of the invention is the provision of a mechanism on a hair clipper of this class which will change the height of its cutters automatically determined by the distance passed along the scalp.

Another object of the invention is the provision of a mechanism on a hair clipper of this class which will change the height of the cutter with different speeds determined by the same distance passed along the scalp.

Another object of the invention is the provision of a mechanism whereby the height of the cutters may be manually changed.

Another object of the invention is the provision of a mechanism whereby the clipper may be used for cutting hair in various styles mechanically.

Another object of the invention is the provision in a machine of this class of a comb mechanism adapted to comb the hair prior to its reception by the cutters, so that long hair may be cut independently of the simultaneous cutting of adjacent short hair.

Another object of the invention is the provision of a stationary comb cooperating with a movable comb for delivering the long hair to the clippers in the most desirable condition for clipping.

Other objects will appear hereinafter.

The invention consists in the combination and arrangement of parts hereinafter described and claimed.

The invention will be best understood from a reference to the accompanying drawings which form a part of this specification, and in which,

Fig. 1 is a side elevational view of the invention.

Fig. 2 is a view taken on substantially line 2—2 of Fig. 1 with parts removed.

Fig. 3 is a view taken on line 3—3 of Fig. 2. 55

Fig. 4 is a fragmentary view similar to Fig. 3 with parts in different position.

Fig. 5 is a view taken on line 5—5 of Fig. 2.

Fig. 6 is a view taken on line 6—6 of Fig. 2.

Fig. 7 is a view taken on line 7—7 of Fig. 6. 60

Fig. 8 is a view taken on line 8—8 of Fig. 4.

Fig. 9 is a view taken on line 9—9 of Fig. 8.

Fig. 10 is a side elevational view reversed to Fig. 1 with parts broken away.

Fig. 11 is a fragmentary sectional view 65 taken on line 11—11 of Fig. 10.

Fig. 12 is a view taken on line 12—12 of Fig. 3.

Fig. 13 is a view taken on line 13—13 of Fig. 3. 70

Fig. 14 is a view taken on line 14—14 of Fig. 3.

The invention comprises a base 18 projecting from opposite sides of which are flanges 19 and 20. Extending upwardly from the forward side of the base are supports 21 and 22 which are inwardly offset as clearly shown in Fig. 2. Extending transversely of the frame is a shaft 23 on which are mounted traction wheels 24 and 25 which engage the 75 scalp when the device is in use. A beveled gear 26 is carried on the outer face of the wheel 25 meshing with a beveled gear 27 which is fixedly mounted on the rod 29 which projects through the journal 28 and extends into the sleeve 33. A journal 30 serves to support the rod 32 which is also journaled in the bar 31. A head 34 mounted on the rod 32 is secured to the sleeve 33 by the pin 35.

(See Fig. 6). Projecting outwardly from the periphery of the rod 29 at that portion which is positioned in the sleeve 33 are ribs 36 and 37 engaging in grooves 38 and 39 formed on the inner surface of the sleeve 33.

A reduced portion 40 of the rod 29 is provided with a disc or abutment member 41 against which engages one end of the spring 42 which is positioned in embracing relation about the member 40, and at the other end of which engages the shoulder 333 formed 85

90

95

99

100

- in the sleeve 33. Formed in the rib 37 is a notch 43 in which is adapted to engage a nose 44 of a latch 45 which is rockably mounted on the sleeve 33. Fixedly mounted on the rod 32 is a gear 46 which meshes with the arcuate rack bar 47 carried by the bracket 48 which extends outwardly from the arcuate member 49 which is slotted and provided at each side of the slot with teeth 50 and 51.
- 5 A shaft 52 serves to swingably mount the finger grip 53 on a projection 53' which extends downwardly from the frame 60. Bar 54 connects the finger grip 53 to one end of the member 49. Secured to the base 18 and 10 projecting upwardly therefrom at opposite sides, are rods 55 and 56, each of which is similarly constructed and operated in a similar manner so that a description of one will suffice for both. The rod 55 is embraced by 15 a spring 57 which extends into a sleeve 58 which is mounted fixedly on the cross bar 59 on which is suitably secured a frame 60 having a cover 61 mounted thereon to provide a grip. A slot 62 is formed in the frame and 20 cover and a presser 63 is carried by the arm 64 which is pivotally mounted at 65' inside a bifurcation formed on the rockably mounted arm 65 having the arcuate portion 66 provided with the teeth 67 for engagement with 25 the angularly turned dog 68 which is formed integral with the finger grip 53. A leaf spring 69 is mounted on cross bar 70 which is positioned within the frame 60, the bar 65 being pivotally mounted at 65'.
- 30 A rod 55 is connected by means of the brace 71 and sleeve 58 to the plate 72 and a similar brace 71' serves to connect the rod 56 to a plate 73. Pivotally mounted on the brace 71' is an arm 71'' carrying an idler 71'''
- 35 to neutralize the tendency of the belt 105 to slip over the faces of the wheels 106 and 104. Projected through the lower end of these plates 72 and 73 and journaled therein is a shaft 74 upon which is mounted at opposite 40 sides gears 76 and 77 each cooperating with similar gears such as 76' which are mounted on the shaft 75 projected through the plates 72 and 73 adjacent their upper ends. These 45 gears engage links 78 and 79 which form a chain attached to a flexible belt 80. One side of the links is extended through the belt as at 81 and 81' and fixedly connected to these extensions is a shaft 82 which extends through knuckles 83 formed on a comb 84.
- 50 A spring 85 (see Fig. 13) is positioned in embracing relation on the rod 82 between the knuckles 83 and has an angularly turned end 86 projecting into the extension 81' so as to normally resist rocking movement of 55 the comb 84 on its pivot, the opposite end being secured to the knuckle 83. Mounted between each of these combs on the belt 80 are presser members 84' constructed as are the combs 84 and similarly mounted except 60 that the teeth are omitted. The spring 85

is of a weaker tension than the spring 85' so that the passage of the comb 84 over the swinging member 125' will not effect the movement of the member 125', while the passage of the presser 84' over the swinging member 125' will push this member 125' rearwardly. A conventional set of electrically operated clippers 210 is used with the invention and secured at its opposite sides are the guide plates 87 and 88, which, as shown in Fig. 1 and Fig. 2 extend forwardly, upwardly, and rearwardly of the clippers, thus preventing the clippings from spreading over the machine. A comb 89 having teeth 89' is hingedly mounted on the plate 87 and 70 locked against the plate 88, the teeth of this comb approximately engaging a brush 90 which is mounted on the rotatable shaft 91. The comb 89 serves to clean the brush 90 from clippings when the mechanism is operated. The brush 90 serves also to clean the pressers 84' and the combs 84 from clippings. (See Fig. 2.)

75 A disc 92 is illustrated and shown clearly in Fig. 11. This disc is mounted on the upper end of a crank shaft inside of the clipper casing and this crank shaft is geared to the flexible or solid shaft of the clippers driven by an electric motor and engages, 80 through its crank portion, one end of a lever pivoted at the point where the usual tightening screw of the conventional pair of clippers is found. A further detail of structure of the clippers is not made, as these clippers are of a well known type and the mechanism thereof would be easily understood by one skilled in the art. As shown in Fig. 11, the driving disc 92 of the clippers engages the periphery of a friction disc 93 which is mounted on a rotatable shaft 94. Projecting outwardly from the plate 88 is a bracket 95 in which is threaded a screw 96, this screw being rotatably connected to the angularly turned end 97 of the slidable yoke tree 97' having the spaced arm 99, this yoke serving 95 as a support and journal for the shaft 94. Fixedly mounted on the shaft 94 is a sheave wheel 101 which is connected by the belt 102 to a sheave wheel 103 fixedly mounted on the shaft 91. (See Fig. 10.) This belt may be 100 made of elastic or stretchable material so that the belt will run in a tensioned condition over the sheave wheels. Fixedly mounted on the shaft 94 is a sheave wheel 104 connected by the belt 105 to the sheave 106 which is fixedly mounted on the rotatable shaft 75. Projecting rearwardly and outwardly from the bar 112 is an arm 111'. Connected pivotally to the arm 111' is a rod 107 carrying at its opposite end a 105 worm wheel 108 which engages in the slot formed in the member 49 and meshes with the teeth 51 and 50 and which may be rotated by the knob 408 on its shaft so that this 110 worm wheel may travel lengthwise of the 115

member 49. The adjustment of the worm wheel 108 in the member 49 serves to determine the height of the clippers regardless of the maximum angularity of the finger grip 53. The worm wheel 108 is fixedly mounted on its shaft which is extended to form the knob 408. Secured to the plates 87 and 88 and projecting outwardly therefrom are bars 109 and 110 each carrying a sleeve or knuckle 109' and 110' respectively, through which is projected the rods 55 and 56. These rods are connected by the cross bars 111 and 112 which serve as reinforcements, and by the cross plate 112' which serves to prevent the hair from spreading on the mechanism positioned below the bar 112'.

Upwardly extending supports 113 and 144 serve as journals for a transversely extending shaft 115, (see Fig. 9) upon which is fixedly mounted a gear 116 meshing with rack teeth 117 formed on a slidable base 118. (See Fig. 3 and Fig. 8.) Fixedly mounted on the forward end of this base 118 is a comb 119 which directs the short hair into the cutters of the clipping mechanism while the slidable base 118 is moved inwardly and which combs the long hair after the slidable base 118 has reached its innermost position on the base 18 and the teeth of the comb 119 come into contact with the skin of the head. An extension 120 is formed on the base plate of the clippers 210 to carry a member 125 which is slidably mounted thereon. Projecting upwardly from the base 118 are spaced brackets 121 and 121' which serve to support a transversely extending shaft 122 on which is wound a flexible clock spring 123 about .003 inch thick, the free end of which is doubled around a roller 124 which is journaled between the said spaced brackets 121 and 121' on the base plate 118. The member 125 is fixedly attached to the spring 123 as shown in Fig. 3 and Fig. 4. Two tongues 126 and 126' which are parallel to the bars 55 and 56 project downwardly from the member 125 and engage in the elongated openings in the plate 127 during outward and inward movement of the slidable base 118 until this base is locked in its innermost position on the base 18. One end of the clock spring 123' is secured to the slidable base 118 and the other end of this spring is secured to the rockable shaft 122, about which is coiled the spring 123' serving to hold the spring 123 in strain and parallel to the base 18 regardless of the pressure exerted upon the spring 123 by the combs 84 and the pressers 84'. Instead of these two springs 123 and 123' only one of the springs 123 may be used, provided its coiled end is thicker than three thousandths of an inch so that it will possess the necessary resiliency and strength. The clippers are shown provided with the conventional cutters or cutter blades 120' and 120''.

Secured to the bar 111 and projecting downwardly is a bar 128 having teeth 129 formed on one edge which mesh with the gear 130 fixedly mounted on the shaft 115 so that as the bar 128 is moved longitudinally, forward or rearward movement of the base plate 118 will be effected, depending upon the direction of movement of the bar 128. As shown in Fig. 8 and Fig. 9 a locking mechanism is mounted for locking this base plate 70 against rearward movement when the bar 128 is disengaged from the gear 130 and comprises a pin 131 which is projected through the inwardly extending brackets 134 which are secured to opposite ends of the support 75 113. A spring 132 embraces the pin 131 and serves normally to retain the angularly turned end 131' in position for engaging in locking position that is, in position to engage the rear edge of the base 118. Mounted on the bar 128 is a pin 133 which is adapted to engage the angularly turned end 131'' for moving the end 131' to inoperative or releasing position. The bar 128 disengages from the gear 130 as, in the tilting operation, the 80 base 118 reaches its inmost position of inward movement.

In operation, the clippers are always moved against the direction of the hair so that the front ends of the frame and the brush wheels 24 and 25 are in contact with the scalp or skin of the head, the comb 119 being in contact with the skin only when long hair is operated upon. When the gears 26 and 27 are in mesh, a pressure on the brush 85 wheels 24 and 25 will be required to ensure the engagement between the skin and these wheels. The gears 26 and 27 are in mesh and are removable so that the device will travel along the scalp and the wheels 24 and 25 will not 90 "spin" or lose traction. When the base 118 is in its rearward position on the frame, the pressure on the finger grip 53 will effect a travel of the gear 46 along the arcuate rack bar 47, thus effecting a rotation of the brush wheels 100 24 and 25, the amount of the rotation being proportionate to the distance the clippers pass over the scalp. The gauge 142 on the wheel 25 will indicate the amount of rotation 105 of the gear 26 by means of the indicator 143 110 so that the distance from a lower marginal line on the head may be known at all times when the clippers are in operation. At the same time, the pressure on the finger grip 53 will effect an upward travel of the clippers 115 along the bars 55 and 56 due to the swinging movement of the trigger 53 and arc 49 which effects a pull on the rod 107 causing the clippers to move upwardly along the bars 55 and 56 against the tension of the springs 57 and 57'. The gauge rule 141, secured to and projecting upwardly from the flange 20, will indicate the amount of tilt by means of the indicator 140 which is attached to the clippers 120 125 210. The ratio of diameters of the gears 26, 27, 120 and 121 is 120 to 125.

27 and 46 is such that the brush wheels make only one revolution while the finger grip 53 is raised to its maximum height.

As the angle of inclination of the rod 107 5 may be determined by adjusting the worm 108 in the arcuate member 49, this adjustment will effect a tilting within pre-determined limits dependent upon the position of the member 108 on the member 49, the rod 107 resisting the tilting of the clippers relatively 10 to the supporting frame beyond a pre-determined degree. Thus the operator, knowing that a certain reading indicated on the scale 49' corresponds to a certain tilt of the 15 clippers 210 to effect a particular style of hair cut, may very quickly adjust the device to cut the hair in various styles. In this way the clippers may be adjusted to vary in depth automatically while pressed over the 20 same distance along the scalp and as many styles of hair cut obtained as would be were the number of divisions on the scales 142, 141 and 49' multiplied.

At the time the upward tilting operation is 25 effected, the rack bar 128 will through its operation on the gear 130, move the base 118 forwardly, thus effecting the inward movement of the member 125 through the pressure of the member 127 on the two tongues 30 126 and 126'.

While at the time of the tilting operation the teeth of the comb 119 which have been moved to their forwardmost position in the 35 frame, come in contact with the skin, the combs 84 and the pressers 84' will come into contact with the swinging part 125' of the spring 123 so that the hair will be inclosed and squeezed between the member 125' on one side and the combs 84 and the pressers 84' 40 on the other side. In this way the operation of the clippers on the long hair begins. The combs 84 will serve to straighten the hair and prepare it for cutting by the clippers without effecting a swinging of the swingable member 125'. The pressers 84' will serve to push 45 the members 125' backward, thus effecting the feeding of the hair to the clippers and resulting in a uniform and neat cutting, because every hair, caught between the teeth of the combs 84 will be pressed toward the clippers by the pressers 84'. As long as the short hair is operated upon, the hair will be raised by the clippers while they are in operation. As long hair is operated upon, every 50 hair which is cut will be forced from the clippers along the spring 123 down to the skin. At the same time every long hair which is to be cut will be fed along the member 123 up to the clippers due to the action of the comb 119, the combs 84 and the pressers 84' 55 combined with the movement of the clippers on the scalp against the direction of growth of the hair. When at the time of tilting operation, the base 118 reaches the limit of its inward movement, the rack bar 128 will be

disengaged from the gear 130 by riding off the same because of its movement bodily with the clippers 210, thus releasing the member 131' and locking the base 118 on the frame through the operation of the member 131' on 70 the bracket 19 of the frame. At the same time the member 125 reaches the limit of its inward movement on the member 120. If the tilting operation is continued, the members 126 and 126' will be disengaged from the member 127 and the member 123 will begin to unwind, the clock spring 123' serving to hold the member 123 in tension, thus limiting outward movement of the member 125. The brush 90 will serve to free the combs 84 from 75 all clippings and the pin like projections 31' on the clippers will prevent downward passage of these clippings so that the path of the clippers is always free from clipped hair. These projections 31' may be formed from 80 thin wire or the like and welded or otherwise secured to the clippers 210. The comb 89 serves to free the brush 90 from all clippings and may itself be manually cleaned.

The springs 57 and 57' will be compressed 85 during the tilting operation, the engagement of the dog 68 with the segment 66 serves to limit the rocking movement of the member 53 and thus determine the amount of tilting 90 which may be effected by the pressure on the finger grip 53. The idler 71'' (see Fig. 10) will serve to overcome the tendency of the belt 105 to slip over the faces of the sheave wheels 106 and 104. Prior to starting an 95 operation on a person's hair, the style of hair cut desired would be made known to the operator. This will determine the initial 100 height of the cut. The operator would know at what original depth the cut should begin. He would also know the adjustment necessary 105 to provide the gradual change of depth of cut. He would then adjust the mechanism by moving the trigger 53 until the proper initial depth was indicated on the rule 141 by the pointer 140. The trigger would 110 then be held in this position by the member 66. The adjustment of the device to indicate the proper reading on the rule 141 should never precede the adjustment on the scale 115 49' as in such instances the worm wheel 108 would not move longitudinally of the member 49 because the member 49 would then be 120 swung into a position where it would no longer form an arc of the circle determined by the worm wheel 108, swinging on the arm 107 125 as a radius. The hair cutting is then begun at the base of the hair line and the trigger 53 would be rocked thus causing a travel of the device over the scalp, and the distance 125 of travel would be indicated on the gauge 142 so that a uniform line of cut, measuring from the base of the hair line, may be maintained throughout. After the trigger 53 is rocked so as to effect a swinging of the member 47 to effect a travel, the tilt of the clip- 130

pers would be varied, and this variation is in proportion necessarily to the distance of travel and the degree of variation of tilt of the clippers will determine the variation in 5 the depth of cut, and this variation is progressively proportionate to the distance of travel. The mechanism therefore is one which eliminates all guess work in making a hair cut, as the variation in depth must of 10 necessity be uniform throughout. The advantages of this mechanism are believed apparent when it is considered that the use of the mirrors to guide the barber and to satisfy the customer in barber shops may be dispensed with. In other words, the human element as affecting the nature of the hair cut 15 is removed.

The backward pressure on the member 63 will return the parts of the machine into 20 their initial position, that is, under pressure, of springs 57 and 57', the travel of the gear 46 along the arcuate rack bar 47 will be reversed, thus effecting the reversal of the brush wheels 24 and 25. At the same time 25 the clippers will travel downwardly along the bars 55 and 56 and the wide spring 123 will be wound on the roller 122. After the tongues 126 and 126' have entered the holes of the member 127, the member 133 of the 30 rack bar 128 will press against the member 131" thus unlocking the base 118 from the base 18. After the rack bar 128 has come in mesh with the gear 130, the outward movement of the base 118 will be effected, thus 35 effecting the outward movement of member 125 through the pressure of the member 127 on the tongues 126 and 126'. At the time of downward travel of the clippers, the pressure of the idler 71''' on the belt 105 will be 40 lessened.

In use, when the gears 27 and 26 are not in mesh pressure between the scalp and the brush wheels 24 and 25 will not be required due to the fact that slippage of the wheels 45 would not effect any change in the uniformity of the clipping of the hair. The pressure on the member 45, (see Fig. 6) will effect the disengagement of the gear 27 from the gear 26 through the action of the spring 42 on the 50 abutment member 41, while the axial pressure on the gear 27 in the direction of the gear 26 will effect the engagement of the gear 27 with the gear 26 through the action of the member 44 on the member 43.

55 When the height of the clippers at which operation is started is greater than the minimum height of the clippers, the machine must be moved along the scalp from a lower marginal line without pressure on the finger grip 60 until the free ends of the hair reach the clippers. In operation, the combs 84 and the pressers 84' are out of the way of the cutters until the swinging member 125' has reached its forward position on the frame. 65 For this reason short hair will, at the same

time, be in the path of the cutters. At the moment the swinging member 125' reaches its most forward position on the frame, the pressers 84' begin to move the member 125' rearwardly. This amount of movement being determined by the thickness of the hair positioned between the member 125' and the pressers 84'. For this reason a continuous clipping of the long and the short hair results. 70

The device is operated so as to have the disc 92 rotate in a clockwise direction only. The screw 96 serves to control the amount of frictional engagement between the disc 92 and the wheel 93 and to thus control or 80 regulate the running speed of the belt 80.

With a machine constructed in this manner, it is thus seen that there is provided a mechanism whereby the depth of the cut may be regulated, whereby this regulation may 85 be manual or automatic, whereby the long hair on account of the engagement of the teeth-bearing plates or combs 84, the pressers 84', the comb 119 and the flexible spring 123 is brought into the teeth of the clippers in uniform condition without effecting the simultaneous cutting of the short hair. 90

In operation the combs 84 and the pressers 84' are out of contact with the skin of the head, the camlike projections 276 on the clippers serving to hold the comb 84 and the presser 84' out of interference with the cutting operation of the clippers. These projections 276 are mounted on the plate 120 and project inwardly from the inner face of the plates 87 and 88 and serve, in some positions of the clippers as engagement members over which the combs 84 and pressers 84' ride. 95

While I have illustrated and described the preferred form of my invention, I do not 105 wish to limit myself to the precise detail of structure shown, but desire to avail myself of such variations and modifications as come within the scope of the appended claims.

Having thus described my invention what I claim as new and desire to secure by Letters Patent is:

1. In a machine of the class described: a clipping mechanism; a frame for supporting said mechanism; and guide plates at opposite sides of said clipping mechanism projecting above, rearwardly and forwardly thereof. 115

2. In a machine of the class described: a clipping mechanism; a frame for supporting said mechanism; a base on said frame; an auxiliary base movable relatively to said frame base; and automatically operated means for moving said auxiliary base. 120

3. In a machine of the class described: a clipping mechanism; a traveling belt; means for effecting traveling of said belt; a plurality of combs spaced apart and mounted on said belt; and a plurality of pressing members mounted each between a pair of said combs on said belt. 125

4. In a machine of the class described: a clipping mechanism; means for supporting said clipping mechanism; and means for adjusting said clipping mechanism upwardly relatively to said supporting mechanism dependent upon the distance moved by said clipping mechanism relatively to a head on which used.
5. In a machine of the class described: a clipping mechanism; supporting means for said clipping mechanism; a base on said supporting means; an auxiliary base movable relatively to said supporting means base; means for moving of said clipping mechanism upwardly relatively to said supporting means; and means for moving said auxiliary base in co-ordination to the variation of the upward movement of said clipping mechanism relatively to said supporting means.
6. In a machine of the class described: a supporting frame; a clipping mechanism mounted on said frame; a slidable base on said frame; means for moving said clipping mechanism upwardly relatively to said frame; and means for sliding said base in co-ordination to the upward movement of said clipping mechanism.
7. In a machine of the class described: a supporting frame; a clipping mechanism mounted on said frame; a plurality of movable combing members; and a rotatable cleaning mechanism for cleaning said combing members as the same pass in engagement therewith.
8. A machine of the class described, comprising: a clipping mechanism; a frame for supporting said mechanism; combing means for combing the hair into said clipping mechanism; and means for moving said combing means upon operation of said clipping mechanism and an auxiliary combing mechanism operated by said first-mentioned combing mechanism.
9. A machine of the class described, comprising; a clipping mechanism; a frame for supporting said mechanism; combing means for combing the hair into said clipping mechanism; pressing means for pressing the hair against the cutters; an auxiliary combing mechanism operated by said first-mentioned combing mechanism; and screw operated means for adjusting and locking said clipping mechanism in various positions.
10. A machine of the class described comprising a clipping mechanism; a frame for supporting said mechanism; means for adjusting the depth of cut of said clipping mechanism; and a combing mechanism for combing toward said clipping mechanism.
11. A machine of the class described comprising a clipping mechanism; a frame for supporting said slipping mechanism; automatically operated means for adjusting the height of said clipping mechanism relatively to said frame to determine the depth of cut;

and a combing mechanism for combing the hair into said clipping mechanism.

In testimony whereof I have signed the foregoing specification.
